SMOKING STAND AND ARTICLE SUPPORT

Benjamin Miller, Philadelphia, Pa., assignor to
 Argo Lamp Company, Philadelphia, Pa., a partnership

Application January 16, 1946, Serial No. 641,491

1 Claim. (Cl. 220—1)

1

This invention relates to a combined smoking stand and article support, and more particularly to a smoking stand which not only provides the customary smoker's facilities, but also provides means for supporting other articles of which a smoker or other user may wish to avail himself.

It is common practice for people who smoke to engage in other pursuits while smoking, such as reading, sewing, sipping a beverage, etc. Very frequently, it is necessary or convenient for the smoker to place the reading matter, beverage glass, or articles of like nature on some nearby support. Conventional smoking stands afford little or no facilities for the reception of such articles.

The primary object of my invention is to provide an improved combination smoking stand and article support which will afford a smoker adequate article receiving as well as the customary smoker's facilities all in one unit which can be placed within easy reach of the smoker.

More particularly, it is an object of my invention to provide an improved combination smoking stand and article support which incorporates (1) space for tobacco products and ashes, and (2) space for reception of cocktail glasses or the like.

Another object of my present invention is to provide an improved combination smoking stand and article support as above set forth which is readily portable and can be placed within easy reach of the user.

A further object of my present invention is to provide an improved combination smoking stand and article support as aforesaid which is simple in construction, which is economical in cost, which can be made highly pleasing in appearance, and which is very efficient in use.

According to one form of my invention, I provide a pedestal which supports an upstanding standard at the upper end of which there is carried a receptacle for tobacco products, such as cigars, cigarettes, etc. This receptacle may be in the form of a humidor, if desired, or it may be merely a casing or housing for the reception and temporary storage of the tobacco products. Surrounding the aforesaid receptacle is an annular tray or support on which cocktail glasses, books, sewing materials or similar articles may be placed. The annular tray is formed to receive an ash tray or the like adjacent its inner peripheral portion and at a point above the aforementioned receptacle. Thus, the ash tray or the like acts as a cover over the receptacle. To facilitate lifting and moving the stand from place to place, the annular tray may be formed with a seat and a

2

handle pivotally mounted thereon for movement from a rest position within said seat to an upright position over said receptacle and ash tray. In its said rest position, the handle is substantially flush with the adjacent portions of the annular tray and is substantially concealed from view, but when it is in its raised or upright position, the handle can be grasped by the hand to facilitate lifting of the stand. In a second form 5 of my invention, a second annular tray may be removably supported on the above mentioned annular tray and provided with suitable handle means to facilitate its removal. This provides a removable tray for empty glasses and like articles.

15 The novel features that I consider characteristic of my invention are set forth with particularity in the appended claim. The invention itself, however, both as to its organization and method of operation, as well as additional objects and advantages thereof, will best be understood 20 from the following description of several embodiments thereof, when read in connection with the accompanying drawings in which

Fig. 1 is a view partly in section and partly in front elevation of one form of combined smoking stand and article support according to my invention,

Fig. 2 is a plan view thereof, and

Fig. 3 is an enlarged, fragmentary section showing one way in which the pivoted handle may be mounted on the article supporting tray.

Referring more particularly to the drawing wherein similar reference characters indicate corresponding parts throughout, there is shown a base 1 which threadedly receives an upstanding tubular core 3. The base 1 is covered by a shell 5 and the core 3 is surrounded by a plurality of interfitting sleeves 7 all of suitably ornamental form. The base 1 and shell 5 constitute, in effect, a pedestal, and the core 3 and shells 7 constitute 35 a standard which rises from the pedestal to a suitable height.

On the upper end of the uppermost sleeve 7, there rests a second shell 9 which is secured to the standard in any suitable manner, as by a nut 11 threaded onto the upper end of the core 3 and intermediate washers 13. The nut 11 also holds the shell 5, the sleeves 7 and the shell 9 in suitably assembled relation. The shell 9 may be formed with a seat 15 on which rests a receptacle 17 in which tobacco products, such as pipe tobacco, cigars or packages of cigarettes 19, may be stored. The receptacle 17 may have an open top, or it may be in the form of a humidor, in which latter case it is provided with a tightly 55 fitting lid 21.

Resting on the shell 9 and secured thereto by means of a plurality of circumferentially spaced bolts 23 and associated acorn nuts 25 is an annular tray 27 which is formed adjacent its inner periphery with an annular recess 29 for a purpose shortly to be set forth. The tray 27 serves to receive and support various articles with which the user may be concerned, such as cocktail glasses 31, wine goblets 33, or books, spectacles, sewing materials and the like (not shown). Beyond the recess 29, the annular tray 27 is provided with a portion 35 which extends inwardly down around the upper end of the receptacle 17 and forms a seat for an ash tray 37. The ash tray 37 serves not only to receive ashes, but also as a cover over the receptacle 17. By removing the ash tray 37, access is provided to the receptacle 17 and its contents.

To facilitate lifting and transporting the combined smoking stand and article support, a semi-circular handle 39 is pivotally mounted on one of the side walls of the groove or recess 29. For this purpose, the outwardly offset, threaded ends 41 of the handle 39 extend loosely through diametrically opposed openings 43 in the tray 27, and a nut 45 is threaded on each handle end 41 to lock the handle 39 to the tray 27. A spring washer 47 is interposed between each nut 45 and the adjacent wall portion of the groove 29 to provide sufficient friction to hold the handle 39 in any position to which it is moved. The handle 39 may be swung in either direction down into one or the other half of the groove 29 which acts as a seat therefor, or it may be swung up into an upright position over the ash tray 37, as shown in Figs. 1 and 2. The dimensions of the groove 29 and the handle 39 are such that when the handle 39 is in its rest position within the groove 29, it is substantially flush with, or perhaps even just slightly below, the surface of the tray 27. In this position, the handle 39 will be substantially concealed from view and will not provide any obstruction to the free and easy removal of the tray 37 about which it will be disposed. On the other hand, when the handle 39 is raised to its upright or vertical position, it can be grasped readily by the hand to facilitate lifting of the entire assembly and, of course, movement thereof from one place to another.

From the foregoing description, it will be apparent to those skilled in the art that I have provided an improved combination smoking stand and article support which affords certain conveniences and advantages not found in similar devices of the prior art. Although I have shown and

described only one embodiment of my invention, it will undoubtedly also be apparent to those skilled in the art that many other modifications, as well as changes in the embodiment shown and described, are possible within the scope of my invention. I therefore desire that my invention shall not be limited except insofar as is made necessary by the prior art and by the spirit of the appended claim.

10 I claim as my invention:

In a device comprising a combined smoking stand and article support, the combination of a pedestal, a standard supported thereon, storage means providing a receptacle carried at the upper end of said standard, an annular tray surrounding said receptacle, said tray being provided with a seat therein adjacent to its inner periphery, a handle pivotally carried by said tray for movement from a rest position within said seat to an upright position over said receptacle and vice versa, said handle being adapted to be grasped by the hand when in said upright position to facilitate lifting said device, and closure means removably supported by said tray above said receptacle constituting a cover over said receptacle, said cover being removable from said tray to provide access to said receptacle and said handle being disposed about said cover when said handle is within said seat.

BENJAMIN MILLER.
